UNITED STATES PATENT OFFICE

ELMER ORLAND AMES, OF TULARE, CALIFORNIA

GEAR HEAD FOR TURBINE PUMPS

Application filed September 5, 1931. Serial No. 561,444.

The present invention relates to well pumping equipment and the primary object of the invention is to provide an improved gear head for turbine deep-well pumps.

5 A further object of the invention is to provide improved supporting and driving means for the pump shaft embodying adjustable features permitting take-up due to wear and permitting vertical adjustment of 10 the pump shaft.

15 A further object is to provide an improved gear head of this character wherein the drive gearing is fully encased in a housing containing a lubricant, with means for cooling the housing to insure long running of the driving mechanism.

20 Other objects and advantages of the invention will be apparent during the course of the following detailed description, taken in connection with the accompanying drawings, forming a part of this specification, and in which drawings,

25 Figure 1 is a side elevation of the improved gear or driving head.

Figure 2 is an enlarged vertical section through the head.

Figures 3 and 4 are reduced sectional views taken on their respective lines in Figure 2.

30 Referring to the drawings in detail and wherein similar reference characters designate corresponding parts throughout the several views, the improved gear head comprises a supporting base 5 embodying a base plate 6 from which extends a depending vertical

35 suction pipe 7. Communicating with the upper end of the suction pipe 7 above the base plate 6 is an L-shaped discharge pipe 8 through which the water is delivered from the suction pipe 7. Supported horizontally

40 above the base plate 6 as by means of legs 9 is a top plate 10 of circular formation as clearly shown in Figure 4. This preferably flat top plate 10 is supported coaxially above the suction pipe 7 and is provided with a plain, axially disposed circular opening 11.

45 Adjustably supported upon the top plate 10 is a gear head proper comprising a gear casing 12 including a tubular body portion 13 being open at its upper side and provided

50 with upper and lower external annular

flanges 14 and 15 respectively. Cast integral with the lower end of the tubular body portion 13 is a tapered or bell portion 16 which terminates in a tubular supporting sleeve 17 the lower end portion of which is threaded both internally and externally. The lower portion of this tubular supporting sleeve 17 extends through the top-plate opening 11 and has threaded thereon a pump shaft adjusting nut 18 adapted to bear upon the upper side of the plate 10. As will readily be apparent, rotation of this adjusting nut 18 permits vertical movement of the gear casing 12 with respect to the supporting base 5.

60 The tubular body portion 13 is closed at its lower end by a bottom wall 19 with which the upper end of the supporting sleeve 17 connects. Arranged inwardly of the outer wall of the tubular body portion 13 is an inner wall 20 providing an annular cooling chamber 21 being closed at its upper end and having communicating openings 22 at its lower end which communicate with a cooling chamber 21' formed by the bell portion 16 and bottom wall 19. These cooling chambers 21 and 21' are provided with suitable ports 23 for the circulation of water through the chambers. An inspection cover 24, bolted to the top flange 14 by suitable bolts 24', provides a chamber 25 for receiving a suitable lubricant, and the drive gearing is arranged in this chamber 25.

70 Arranged within the chamber 25 and preferably cast integral with the bottom wall 19 is a pair of upstanding bearing bracket arms 26 for mounting of a drive shaft 27 extending radially of the tubular body portion 13. Splined on the drive shaft 27 between the bracket arms 26 is a bevel drive gear 28 having a hub portion 29 abutting at its ends with anti-friction thrust bearings 30 arranged in the bracket arms 26. Associated with each thrust bearing is a thrust adjustment nut 31, and these nuts 31 permit axial adjustment of 75 the bevel drive gear 28. A flange bearing 32 supports the drive shaft 27 where it extends through the gear casing, and a packing gland 33 is threaded into the flange bearing to prevent leakage of lubricant along the shaft. 80

85 90 95 100

A vertically extending pump shaft 34 is intended to extend axially through the supporting sleeve 17 into the gear casing chamber 25. The pump shaft 34 extends through the bend in the discharge head 8 and a suitable packing gland 35 is provided where the shaft extends through the bend. Secured to the upper end of the pump shaft 34 is a bevel pinion 36 for meshing with the bevel drive gear 28, and a suitable retaining nut 37 retains the pinion 36 on the pump shaft.

Threaded into the lower end of the tubular supporting sleeve 17 is an adjustable bearing cage 40 having a sleeve portion 41 provided with an internal annular ring seat 42 for receiving an anti-friction thrust bearing 43 having its inner race carried by the pump shaft 34. Arranged in spaced relation above the thrust bearing 43 as by suitable spacing bushings 44 is an upper anti-friction thrust bearing 45 through which the pump shaft 34 extends.

The bevel pinion 36 is provided at its lower side with a short hub adapted to rest upon the inner race of the upper thrust bearing 45, as clearly shown in Figure 2. Thus it will be seen that the adjustable bearing cage 40 serves to support the pump shaft.

The lower end of the bearing cage 40 is formed with a wrench square 46 whereby the cage may be rotated and threaded up or down in the sleeve 17. A packing gland 47 is threaded into the lower end of the bearing sleeve to prevent escape of lubricant along the shaft 34. The thrust bearings 43 and 45 will be lubricated by the lubricant in the chamber 25. An adjustment lock screw 48 is threaded through the supporting sleeve 17 into engagement with the bearing cage for locking the bearing cage in its adjusted position.

Connected between the lower casing flange 15 and the peripheral portion of the top plate 10 is a series of combined lock and brace rods 50. These brace rods 50 have heads at their upper ends which rest on the upper side of the flange 15 and have screw-threaded lower ends which extend through the top plate 10 and are adapted to receive nuts 51 intended to be turned into engagement with the under side of the top plate. These rods 50 aside from bracing the gear casing 12 serve as locks for the adjusting nut 18 thus creating a clamping action between the nut 18 and the top plate 10 through tightening of the nuts 51. The threaded lower end of the brace rods 50 also permits vertical adjustment of the gear casing 12 relative to the supporting base 5.

Thus it will be seen that through rotation of the adjustment nut 18, the gear head may be bodily adjusted vertically, and the pump shaft 34, which is suspended by the gear head, will also be vertically adjusted. Rotation of the cage 40 will permit of the desired

meshing engagement of the bevel pinion 36 with the bevel gear 28, and further adjustment of the gears is had through adjustment of the adjusting nuts 31, which permits axial adjustment of the gear 28.

Thus it will be seen that an improved gear head for turbine pumps has been disclosed embodying novel features of adjustment permitting vertical adjustment of the pump shaft and adjustment of the drive gearing to compensate for any wear. It will also be apparent that a novel arrangement has been disclosed whereby the drive shaft may be disposed in a horizontal position at a right angle to the pump shaft for connection to any source of motor power.

Changes in detail may be made without departing from the spirit of the invention or the scope of the claims.

I claim:

1. In rotary pumping equipment, a supporting frame including a top plate, a drive head including a casing, means supporting the casing axially upon the top plate and permitting vertical adjustment of the casing, adjustable brace rods connecting the casing to the top plate, a drive shaft journaled horizontally in the casing, a rotary pump shaft journaled in the casing and suspended from the casing, and drive gearing in the casing for imparting rotation to the pump shaft from the drive shaft.

2. In rotary pumping equipment, a supporting frame including a top plate, a drive head comprising a gear casing and a tubular externally threaded supporting sleeve depending from the gear casing, an adjusting nut threaded on the supporting sleeve and resting upon the top plate, adjustable brace rods connected between the drive head and top plate, a drive shaft journaled horizontally in the casing, a pump shaft journaled in the supporting sleeve and pendently supported by the drive head, and drive gearing between the drive shaft and contact shaft.

3. In rotary pumping equipment, a supporting frame including a top plate having an opening therethrough, a drive head including a gear casing and a tubular externally threaded supporting sleeve extending through the opening in the top plate, a nut threaded on the supporting sleeve and bearing upon the top plate, adjustable brace means between the drive head and supporting frame, a drive shaft journaled horizontally in the casing, a bearing cage vertically adjustable in the supporting sleeve, a contact shaft journaled in the supporting sleeve and supported thereby, a bevel pinion fixed on the upper end of the contact shaft within the gear casing, and an axially adjustable bevel drive gear on the drive shaft for meshing with said bevel pinion.

4. In rotary pumping equipment, a supporting base, a drive head casing vertically

adjustable on the base and including an internally threaded depending supporting sleeve, a bearing cage vertically adjustable in the supporting sleeve, an adjustment locking screw for the bearing cage, a drive shaft journaled horizontally in the gear casing, a bevel drive gear on the drive shaft, a pump shaft journaled in the bearing cage and supported thereby, and a bevel pinion fixed on the upper end of the pump shaft for meshing with the drive gear.

5. In a turbine pump, a supporting frame,
